UNITED STATES PATENT OFFICE

108,055

DESIGN FOR A COMBINED WHEEL AND TIRE

James V. Martin, Hempstead, N. Y.

Application April 18, 1936, Serial No. 62,193
In Canada January 28, 1936

Term of patent 14 years

To all whom it may concern:

Be it known that I, James V. Martin, a citizen of the United States, residing at town of Hempstead, Nassau County, in the State of New York, have invented a new, original, and ornamental Design of a Combined Wheel and Tire, of which the following is a specification, reference being had to the accompanying drawings, forming part thereof.

Fig. 1 is an outside elevational view of a combined wheel and tire showing my new design, the conventional wheel portion being illustrated in dotted lines.

Figs. 2 and 3 are enlarged views, respectively in section and perspective, showing one of the spoke members illustrating the cross diagonal ribs.

Fig. 4 is an enlarged outside perspective view of one-half of the combined wheel and tire.

The characteristic feature of my design resides in the tire portion shown in solid lines in Fig. 1 of the drawings.

I claim:

The ornamental design for a combined wheel and tire, as shown and described.

JAMES V. MARTIN.
